UNITED STATES PATENT OFFICE.

RAY W. ELDREDGE, OF ORLEANS, VERMONT.

HANDKERCHIEF-DISPLAY CASE.

Application filed June 11, 1925. Serial No. 36,510.

This invention relates to an improved display case for handkerchiefs and seeks, among other objects, to provide a neat, inexpensive and compact device of this character which may be set upon a show case, for instance, in a store, or upon a counter or the like, for attractively displaying handkerchiefs for sale.

The invention seeks, as a further object, 10 to provide a device embodying an individual box for each handkerchief, so that the handkerchiefs will be kept clean and sanitary, and wherein the container for the boxes will be formed to deliver the boxes one at a time.

15 And the invention seeks, as a still further object, to provide a device wherein the container may be readily reloaded and wherein, as the handkerchiefs are sold and the boxes are removed from the container, the boxes 20 remaining in the container will feed downwardly therein for successive delivery.

Other and incidental objects will appear hereinafter.

In the accompanying drawings:

25 Figure 1 is a perspective view of my improved display case.

Figure 2 is a vertical sectional view on the line 2—2 of Figure 1, looking in the direction indicated by the arrows.

30 Figure 3 is a transverse sectional view on the line 3—3 of Figure 1, the handkerchief boxes being removed from the container.

Figure 4 is a detail sectional view on the line 4—4 of Figure 2, looking in the direction indicated by the arrows.

Figure 5 is an edge elevation showing the prop of the container folded.

Figure 6 is a longitudinal sectional view through one of the handkerchief boxes.

40 Figure 7 is a detail perspective view showing an end of one of the handkerchief boxes and illustrating the closure flaps thereof.

In carrying the invention into effect, I employ a relatively flat oblong container 45 having a front wall 10, a back wall 11, and side walls 12. The container is preferably formed from a cardboard blank, although other suitable material may be employed, and, as shown in Figure 3, the overlapping 50 longitudinal margins of the blank are secured together at one of the side walls of the container. Closing the container at the ends thereof are side flaps 13 integral with the

side walls 12 and end flaps 14 integral with the front wall 10.

55 As shown in Figure 1, the front wall 10 of the container is provided at its lower end portion with a substantially rectangular sight opening 15 defining relatively narrow front flanges 16 at the sides of said opening, and formed in the side walls 12 of the container at the lower ends of said flanges are semi-circular notches 17. Below said notches, a portion of the front wall 10 remains to provide a cross strip 18 at the lower 60 end of the opening 15.

65 Adhesively or otherwise secured to the back wall 11 of the casing is a prop which is also preferably formed of cardboard and comprises a leg 19, base 20, and a spreader 21 provided at its free end with a reduced tongue 22 insertable through a slot 23 located medially of the leg. A single strip of material is preferably employed to form the prop and one end of the strip is secured to the 70 back wall 11, as indicated at 24, for swingingly mounting the leg 19 while the intermediate portion of the strip, as indicated at 25, is secured to said wall at the lower end of the container for swingingly mounting the base 20 as well as the spreader 21. At 75 a point midway between its ends, the base is provided with a transverse crease 26 so that by removing the tongue 22 of the spreader 21 from the slot 23 of the leg 19, the spreader may, as shown in Figure 5, be 80 folded against the back wall of the container, when the base 20 of the prop may be doubled upwardly at the crease 26 and the leg 19 swung in toward the base to lie close thereto.

85 Thus, the prop may be folded to occupy a minimum space. However, as will be appreciated, the spreader 21 will normally maintain the prop extended so that the base 20 thereof may be rested upon a show case, 90 counter, or the like, for supporting the container in vertical rearwardly inclined position.

95 Slidably fitted within the container is a plurality of individual handkerchief boxes 100 27 of rectangular configuration. These boxes are also preferably each formed of a cardboard blank having side and end flaps 28 and 29 closing the box at the ends thereof. As suggested in Figure 2, each of the boxes 105 27 contains a handkerchief, and said boxes

rest one upon the other within the container. Preferably, the container is of a length to hold at least a dozen of the boxes 27 but, of course, this detail may be varied as found desirable.

As shown in Figure 2, the front strip 18 at the lower end of the container is of a width corresponding to the width of the handkerchief boxes 27 respectively, so that 10 the bottom box at the lower end of the container thus supports the next adjacent box flush with the upper edge of said strip. Furthermore, as will be observed, the distance between the lower ends of the flanges 16 of 15 the front wall 10 of the container and the upper edge of said strip is slightly greater than the width of the handkerchief boxes respectively, so that a discharge slot is defined between the lower ends of said flanges 20 and said strip. Accordingly, the box presented at said slot may be grasped at its ends by the thumb and finger and the box removed forwardly through the slot. As will be perceived, the boxes can be removed 25 only one at a time and each time a box is removed the boxes thereabove will slide downwardly within the container so that

the next adjacent box will be presented at the discharge slot of the container ready for removal. By opening the flaps at the upper 30 end of the container, the container may be readily reloaded.

Having thus described the invention, what I claim is:

A flat oblong casing for displaying articles 35 provided with means for supporting it upon end in upright position, and having a sight opening in the lower portion of its front and retaining flanges at opposite sides of the sight opening, said flanges terminating a distance from the bottom of the sight opening 40 to provide a discharge slot, and having finger notches in the side walls in line with the said discharge slot and a cross strip connecting the bottom and side walls below 45 the discharge slot an article resting upon the bottom of the casing with its upper surface in a plane with the upper edge of the cross strip to support the article immediately thereabove in a position for delivery through 50 said slot and across the bar.

In testimony whereof I affix my signature.

RAY W. ELDRIDGE. [L. S.]
